UNITED STATES PATENT OFFICE.

JOHN HAWLEY TAUSSIG, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

DOOR MECHANISM FOR VERTICAL RETORTS.

1,140,339.

Specification of Letters Patent.

Patented May 18, 1915.

Application filed January 20, 1913. Serial No. 743,025.

To all whom it may concern:

Be it known that I, JOHN HAWLEY TAUSSIG, a citizen of the United States, residing at the city of Philadelphia, in the county 5 of Philadelphia and State of Pennsylvania, have invented a certain new and useful Door Mechanism for Vertical Retorts, of which the following is a specification.

Usually vertical retorts are arranged in 10 rows and several rows are mounted in each bench or setting and there are many benches at a gas works. The doors that close the discharge ends or mouths of the retorts are necessarily inconveniently located beneath 15 the setting, are heavy and exposed to heat and dust or dirt and have to be frequently opened and tightly closed so that in a gas works or plant the operation of a number of such doors presents difficulties.

20 The principal object of the present invention is to provide for operating the discharge doors of vertical retorts, either singly or in rows, from a convenient place or places and with a comparatively small number of 25 attendants and in a rapid and satisfactory manner notwithstanding the fact that the doors are inconveniently located and the further fact that the doors and mechanism that works them are exposed to heat and 30 consequent warping and twisting and to dust and dirt and consequent jamming.

The invention will be claimed at the end hereof but will be first described in connection with the embodiment of it chosen from 35 other embodiments for illustration in the accompanying drawings in which—

Figure 1, is a diagrammatic view illustrating features of the invention. Fig. 2, is a front view, partly in section, illustrating 40 details of construction. Fig. 3, is a plan view of the under side of a door with parts in section. Fig. 4, is a front view of a door. Fig. 5, is a sectional view taken on the line 5—5, of Fig. 4. Fig. 6, is a side view showing one form of clamp. Fig. 7, is a side view showing the arrangement of several 45 clamps, and Figs. 8 and 9, are a side view, partly in section, and a perspective view illustrating a modification.

50 In the drawings 1, are revoluble shafts and there is one such shaft for each row of retorts. These shafts are carried in suitable bearings and as shown they consist of sections connected by universal joint devices

2, and therefore movable in respect to each 55 other. The advantage of making these shafts in the manner described is that they remain operative even if their bearings get out of alinement or the shafts become warped, for example, by reason of the heat 60 and dust or dirt to which the parts are exposed.

3, are cotter bars or door carriers independently hinged in respect to each of said shafts. As shown the shaft for each row of 65 retorts passes through openings in the forked end of the cotter bars that appertain to the row of retorts to which the shaft belongs.

4, are projections or lifting means between the shafts and their complemental cotter bars for lifting the latter toward clamp engaging position and permitting of return movement. As shown the lifting means comprise projections from collars 75 keyed to the shafts 1, Fig. 4, and adapted to each engage a cotter bar.

5, Fig. 4, is a removable liner or piece between the bars and projections for independently adjusting the bars to compensate 80 for irregularity in them or in the parts with which they coöperate. The liner 5, is shown as applied to the operative face of each projection and one liner can be removed and a thicker or thinner one, as may 85 be required, substituted.

6, is a power device provided with a link or transmission 7, common to all the revoluble shafts 1. As shown the power device comprises a hydraulic cylinder and piston 90 controlled by the four-way valve 8, and its connections and operative, for example, by way of the bell crank lever 9, and rod 10, to shift the link 7. There are couplings 11, between the link or transmission and each 95 shaft 1, whereby any shaft may or may not be turned at will. The couplings are shown to comprise pawl arms 12, connected with the link 7, and movable concentrically with and independently of the shafts 1, and provided with pawls 13, that may be made to engage or disengage a tooth 14, on each of the shafts 1. There are long range clamps indicated at 15, Fig. 1, for engaging the free ends of each cotter bar to bring the 105 latter to closing position. There are separate rods 16, for actuating each clamp and the manually operated ends or handles 16^a,

of the rods for each row of retorts are arranged in proximity with each other and are accessible from at or near the couplings 11.

17, are controllers for the power device 5 and they are operated from positions near the couplings. As shown the controller consists of hand levers connected with a rod 18, attached to the plug of the four-way cock 8.

Figs. 3, 4, 6 and 7, illustrate a long range 10 swing clamp of one construction, and Figs. 8 and 9, illustrate a modification. Referring to Figs. 3, 4, 6 and 7, the clamp comprises a link 19, pivotally connected to the free ends of duplicate cantalivers 20. 21 15 and 22, are eccentric straps or followers respectively pivoted to the cantaliver at one end and at the center. On the rod 16, are the eccentrics 23 and 24, for these straps or followers. The eccentric 24, is made in two 20 parts arranged on opposite sides of a bearing 25, and the strap or follower 21, is bifurcated or forked for coöperation with these parts. There are lugs or projections 26 and 27, which when the rod 16, is turned 25 serve to swing the clamp as a whole including the link 19. The projections 26, are shown as formed on a collar on the rod 16, and the projections 27, are shown as formed on the strap, follower or part 21. These 30 projections serve when the shaft is turned to swing the clamp under and clear of the free end of the cotter bar. Continued turning of the rod 16, turns the eccentrics which are fast to it and the eccentrics in turning turn 35 the cantalivers 20, and the link 19, and this they do by moving the two points where the cantalivers are fulcrumed. The purpose of giving the clamp this long range of action is to insure its moving the cotter bar 40 properly even though the latter is warped or bent.

As shown in Figs. 8 and 9, the clamp comprises wedges 28, which engage the ends of the cotter bars and operate through a long 45 range.

By reference to Fig. 7, it will be noted that the ends of the cotter bars which are engaged by the clamps are at different levels and in this way the rods 16, may be made 50 straight and arranged near together and yet clear of each other. The doors 30, are carried by the cotter bars and they may be connected to them by means of eccentrics and straps 31, operated by handles 32. The 55 doors shown in the drawings as well as certain gas off-takes 33, in the door frames are not claimed herein as they form the subject-matter of my application serially numbered 743,027 nor is the specific construction 60 of clamp shown in Fig. 6, and described above specifically claimed herein, as it forms the subject-matter of my application serially numbered 743,026.

In use the doors of any row may be opened 65 by turning the shaft 1, in such position that

its projections 4, are downward and then turning or properly operating the handle 16^a, of the rods 16, so as to cause the clamps to clear the cotter bars. Of course if it is not desired to open the door of any retort, 70 its corresponding handle 16^a, is not moved. To close the retort doors or any of them of a row the shaft 1, of that row is coupled to the link or transmission 7, and the controller 17, is moved to cause the power 75 device 6, to turn the shaft 1, and thus cause its projections 4, to swing the doors upward. All of the cotter bars or some of them, as preferred, are then clamped by the described operation of the clamps. Of course the eccentrics 31, are to be properly 80 operated for assisting in the operation of the doors.

Obviously changes may be made in details without departure from the invention which 85 I do not desire to limit except of course as the prior state of the art may require, but

What I claim is:

1. Door mechanism for vertical gas retorts comprising the combination of a row 90 of independently hinged door carriers, means common to said carriers for turning all of them, devices for adjusting each carrier in respect to said means, and an individual clamp for each carrier. 95

2. Door mechanism for vertical gas retorts comprising the combination of a row 100 of independently hinged door carriers, flexible means common to said carriers for turning all of them into clamp engaging position, devices for adjusting each carrier in respect to said means, and individual long range clamps for engaging each carrier even though warped.

3. Door mechanism for vertical gas retorts comprising the combination of a revolute shaft, a cotter bar hinged to said shaft, a projection on the shaft for lifting the cotter bar, a clamp for clamping the cotter bar, and a removable liner between the bar 105 and projection, substantially as described. 110

4. Door mechanism for vertical gas retorts comprising the combination of revolute shafts each common to a row of retorts, cotter bars independently hinged in 115 respect to said shafts, projections between the shafts and their complemental cotter bars, a power device provided with a transmission common to a number of revolute shafts, couplings between the transmission and each shaft, individual clamps for the cotter bars, separate rods for operating each clamp, and a controller in proximity with the couplings and rods for operating the power device. 120

5. Door mechanism for vertical gas retorts comprising the combination of revolute shafts each common to a row of retorts and consisting of sections movable in 125 respect to each other, cotter bars independ- 130

- ently hinged in respect to said shafts, projections between the shafts and their complementary cotter bars, a power device provided with a transmission common to a 5 number of revoluble shafts, couplings between the transmission and each shaft, individual clamps for the cotter bars, separate rods for operating each clamp, and a controller in proximity with the couplings 10 and rods for operating the power device.
6. Door mechanism for vertical gas retorts comprising the combination of revoluble shafts each common to a row of retorts, cotter bars independently hinged in 15 respect to said shafts, projections between the shafts and their complementary cotter bars, a power device provided with a transmission common to a number of revoluble shafts, couplings between the transmission 20 and each shaft, individual clamps for the cotter bars, separate rods for operating each clamp, a controller in proximity with the couplings and rods for operating the power device, and removable liners between the 25 cotter bars and projections for independently adjusting the cotter bars.
7. Door mechanism for vertical gas retorts comprising the combination of a power shaft having projections, a row of door carriers turnable on the shaft and disconnected 30 from the projections and adapted to contact therewith, a clamp for each door car-
- rier, and individual means for each clamp for causing it to free or engage its door carrier, whereby any door or doors may be held 35 shut while the other door or doors are opened and shut, substantially as described.
8. Door mechanism for vertical gas retorts comprising the combination of a power shaft having projections, a row of door carriers turnable on the shaft and disconnected 40 from the projections and adapted to contact therewith, a clamp for each door carrier, and individual rods arranged substantially parallel with the shaft and extending to the end of the row and each connected with one of said clamps, substantially as described. 45
9. In door mechanism for vertical gas retorts the combination of a row of door carriers, means adapted to simultaneously turn all of the carriers of the row into door closing positions and adapted to release all the carriers to permit those that are unclamped 50 to return to open door position, individual clamping devices for engaging and disengaging and tightening each of the carriers, and a separate means for working each clamping device, substantially as described. 55
